UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

SEWING-MACHINE.

1,145,620.

Specification of Letters Patent.

Patented July 6, 1915.

Application filed June 12, 1909. Serial No. 501,817.

To all whom it may concern:

Be it known that I, DUDLEY S. SEYMOUR, a citizen of the United States, residing at Oak Park, in the county of Cook, State of Illinois, have invented certain new and useful Improvements in Sewing-Machines, of which the following is a description, reference being had to the accompanying drawing and to the letters and figures of reference marked thereon.

The invention relates to new and useful improvements in sewing machines, and more especially to sewing machines of the tubular work support type, although it will be obvious that from certain aspects of the invention, my improvement may be embodied in any type of sewing machine.

An object of the invention is to provide a feeding mechanism with a feed dog which is moved forward in substantially a right line to feed the material, and is then quickly dropped beneath the work support and returned to the forward end of its stroke, where it is quickly raised above the work support into engagement with the material, ready for its feeding action.

A further object of the invention is to provide a tubular work support with a feeding mechanism which is located in the work support and which has a feed dog which may be given a forward movement in substantially a right line to feed the material.

A further object of the invention is to provide a sewing machine having a tubular work support with a feeding mechanism including a feed dog which may be given a relatively long feeding stroke.

These and other objects will in part be obvious and will in part be hereinafter more fully described.

In the drawings which show by way of illustration one embodiment of the invention, Figure 1 is a front side elevation with the parts in section, of a sewing machine embodying my invention. Fig. 2 is a top plan view of the tubular work support with the cloth plate and top portion removed. Fig. 3 is an end view of the work support with the end plate and cloth plate removed. Fig. 4 is a similar view showing the parts in another position. Fig. 5 is a sectional view on the line 5-5 of Fig. 2. Fig. 6 is a sectional view on the line 6-6 of Fig. 2. Fig. 7 is a sectional view on the line 7-7 of Fig. 2. Fig. 8 is a detail view of the feed dog

supporting frame. Fig. 9 is a diagrammatic view showing the essential elements of the feeding mechanism; Fig. 10 is a sectional view of the securing means for the feed-lifting lever; Fig. 11 is a similar view of a modified form of securing means; and Fig. 12 is an end view of the eccentric connecting pair.

The sewing machine as herein illustrated, comprises a standard 1, from which projects an overhanging arm 2. The needle bar 3 carrying the needle 4, reciprocates in the forward end of the overhanging arm 2, and receives its movements from the needle lever 5 which in turn is operated by a link 6, connected with an eccentric on the main shaft 7 of the machine. These parts are of the usual construction and will not need further description.

As herein illustrated, a tubular work support 8 is carried by the standard 1, and projects underneath the needle head of the machine. The main shaft 7 extends through the standard 1 and into the tubular work support and carries at its forward end a crank disk 9. Coöoperating with the needle 4 is a looper 10. Said looper 10 is carried by a looper carrier 11 which is pivoted to a bracket carried by the forward end of a shaft 12, mounted in the tubular work support. The other end of the shaft 12 is provided with a fork 13, which engages a cam 14 on the shaft 7. As the shaft rotates, the fork 13 will be oscillated and will in turn oscillate the bracket supporting the looper 10 and give to the looper the usual needle avoiding movement. The looper carrier is oscillated on its supporting bracket by means of a link 15 which is pivoted to a rock shaft 16. The rock shaft 16 is in turn pivoted upon a bracket 17 and is oscillated through a link 19 connected to the needle lever extension 20. This looper operating mechanism forms no part of the present invention and will not need further description. The looper thread is led through a suitable tension 21 and through guide eyes 22 on the needle lever extension and is then led through suitable guide eyes 22^a to the looper. The needle thread passes through the tension 23, and through the guide eyes 24, 24, on the needle lever. From thence the needle thread passes to the usual needle eye at the top of the needle bar and to the needle.

My improved feeding mechanism consists

of a feed dog 25 which operates through the usual slot in the throat plate to engage and move the material. Said feed dog 25 is carried by a feed dog supporting frame 26 (see Figs. 2 and 8). The feed dog supporting frame 26 is pivoted at its front end to a rocking arm 27 which in turn is pivoted at 28 to a bracket 29 formed on the inner face of the tubular work support. Said feed dog supporting frame 26 is provided with a laterally extending arm 30 which carries a feed dog at its outer end.

The feed dog carrying frame 26 is pivoted near its front end to a link 31 by means of a pivot pin 32. The other end of the link 31 is connected by a pivot pin 33 to an arm 34 carried by a rock shaft 35. The other end of the rock shaft 35 carries a fork 36 (see Figs. 2 and 7), which work coöperates with a cam 37 carried by the main shaft 7. As the cam 37 rotates with the main shaft 7, the shaft 35 will be oscillated raising and lowering the link 31 and thereby raising and lowering the front end of the feed dog carrying frame 26. The feed dog is given its forward and backward movements from the crank disk 9 on the end of the shaft 7. The crank disk carries a crank pin 38 (see Fig. 6) which may be adjustable in the usual manner in the slotted crank disk, in order to change the throw of the crank pin. Coöperating with the crank pin is a link 39, which carries at its other end an eccentric pin 40 which is adjustably mounted in a bearing 41 in the feed dog carrying frame. As the shaft 7 rotates, the feed dog carrying frame will be moved back and forth through the link 39.

In Fig. 9 I have shown in outline the arrangement of the links and levers for moving my feed dog. Starting with the parts as shown in this view the feed dog will be at the forward end of its stroke by reason of the fact that the crank pin 38 has reached its extreme throw in one direction. At this time, the arm 31 is at substantially the upper part of its stroke and the cam 37 is coming into action to oscillate the arm 34. A cam 37 as clearly shown in Fig. 7, is provided with two comparatively long concentric portions so that in the oscillation of the fork 36, it will be moved quickly in one direction, given a comparatively long dwell, then moved quickly in the opposite direction and then given a long dwell. When the crank pin has reached the position shown in Fig. 9, the feed dog is at a dwell so far as its forward movements are concerned, and at this time, the cam 37 operates by swinging the arm 34 downward, to quickly lower the feed dog beneath the work support. The feed dog is then returned to the right hand end of its stroke as viewed in Fig. 9 by the continued movement of the crank pin 38. Just as the feed dog is reach-

ing the extreme right hand throw, the cam 37 again operates to quickly raise the lever 34 and bring the feed dog into engagement with the material. A concentric portion of the cam then comes into coöperation with the fork 36 and the feed dog will be held substantially at a dwell so far as its vertical movements are concerned, while it is being moved forward to feed the material. Inasmuch as the feed dog carrying frame 26 is supported by the link 31 and arm 27 which swing together back and forth from one side of a vertical line to the other side thereof, it will be evident that the oscillating movement of these parts will have little or no effect upon the movements of the feed dog.

By providing a feed dog operating mechanism wherein the feed dog substantially completes its forward movement before it is dropped beneath the work support, I am able to provide a feeding mechanism for a cylinder machine, wherein the feed dog will have a comparatively long straight movement for feeding the material.

In certain classes of work, such for example, as closing the mouths of filled bags, it is very desirable to use a feeding mechanism in connection with a tubular work support, wherein the feed dog has a comparatively long straight movement so that the mouth of the bag will be fed rapidly and positively and that comparatively long stitches may be made which are sufficient for closing the mouth of the bag.

It will be seen that the rocking arm for supporting one end of the feed dog carrying frame, is located at one side of the tubular work support, while the rock shaft for giving the up and down movements to the feed dog, is located at the other side of the tubular work support. By this arrangement of parts, I am able to place within the restricted available space in a cylinder bed plate, a four motion feed dog in which the feed dog may be given a substantially straight line feeding movement. The looper mechanism it will be noted is supported on a shaft located between the rock shaft and rocking arm of the feeding mechanism, and the link for vibrating the looper also extends between these parts. It will also be noted that the main shaft terminates with the crank pin carrying disk so that a sufficient space is afforded for the locating of the feed dog carrying frame. I have also made the upper face of the work support or bed plate flat so that the feed dog may be given a straight line movement which is substantially parallel with the upper face of the work support. The arm 34 for raising and lowering the feed dog, is secured to the shaft 35 by means of set screws 34^a and 34^b. The shaft has a flattened portion, and it will readily be seen that by adjusting the

set screws, the arm 34 may be shifted on the shaft 35, thus raising or lowering the feed dog relative to the work support.

In Fig. 11, I have shown the arm 34 secured to the shaft 35 by spot screws 34^a and 34^b, which engage recesses 34^c. By adjusting the spot screws, the arm 34 may be shifted on the shaft 35, and the working position of the feed dog relative to the work support varied. The eccentric pin 40, as above noted, is adjustably secured to the feed dog carrying frame 26 by screws 40^a. By adjusting the position of the pin 40, the working position of the feed dog relative 15 to the needle may be varied.

Having thus particularly described my invention, what I claim as new and desire to secure by Letters Patent, is:—

1. A sewing machine including in combination, a tubular work support having a flat fabric-supporting surface, a rotating shaft extending into said work support and terminating short of the end thereof, a feed dog carrying frame located in the space beyond the end of said shaft, a rocking arm supporting one end of said frame, a feed dog carried adjacent the other end of said frame, means for raising and lowering said other end of said frame, and means independent 25 of the rocking arm for connecting said shaft to said frame for moving the same back and forth, the means for moving the frame back and forth and the means for raising and lowering the end of the frame being timed 30 so as to give a substantially straight feeding movement to said feed dog.

2. A sewing machine including in combination, a tubular work support, a feeding mechanism located within said work support including a feed dog, a feed dog carrying frame, a rocking arm located at one side of the work support, and pivoted to said frame, a rock shaft located at the other side of the work support, and connected to said frame, a looper, a looper carrier, a rock shaft for supporting said looper carrier located between said first named rock shaft and said rocking arm.

3. A sewing machine including in combination, a tubular work support, a feeding mechanism located within said work support including a feed dog, a feed dog carrying frame, a rocking arm located at one side of the work support, and pivoted to said frame, a rock shaft located at the other side of the work support and connected to said frame, a looper, a looper carrier, a rock shaft for supporting said looper carrier located between said first named rock shaft and said rocking arm, and means for rocking said looper carrier, including a link extending underneath said feed dog carrying frame.

4. A sewing machine including in combination, a tubular work support having a flat fabric-supporting surface, a rotating

shaft extending into said work support and terminating short of the end thereof, a feed dog carrying frame located at the end of said shaft, a crank pin carried by said shaft, a link connected to said crank pin and to 70 said frame, a rocking arm supporting one end of said frame, a feed dog carried by the other end of said frame, and means for raising and lowering said feed dog, said means being timed relative to said crank pin, 75 whereby said feed dog is given a substantially flat feeding movement.

5. A sewing machine including in combination, a tubular work support, a rotating shaft extending into said work support and terminating short of the end thereof, a feed dog carrying frame located at the end of 80 said shaft, a crank pin carried by said shaft, a link connected to said crank pin and to said frame, a rocking arm supporting one 85 end of said frame, a feed dog carried by the other end of said frame, a link connected to said feed dog carrying frame adjacent its free end, and means connected to the lower end of said link for bodily raising and lowering the same.

6. A sewing machine including in combination, a tubular work support, a rotating shaft extending into said work support and terminating short of the end thereof, a feed 95 dog carrying frame, located at the end of said shaft, a crank pin carried by said shaft, a link connected to said crank pin and to said frame, a rocking arm supporting one end of said frame, a feed dog carried by the 100 other end of said frame, a link connected to said feed dog carrying frame adjacent its free end, and means connected to the lower end of said link for bodily raising and lowering the same, including a rock shaft, an 105 arm carried by said rock shaft and pivoted to the lower end of said link for raising and lowering the said link.

7. A feeding mechanism including in combination a feed dog carrying frame, a rocking arm to which said frame is pivoted at one end, a feed dog carried by the other end of said frame, means pivoted to the frame between the feed dog and the rocking arm, for moving said frame back and forth, and means connected to the feed dog carrying frame between the feed dog and the rocking arm, for moving said feed dog carrying frame up and down.

8. A feeding mechanism, including in 120 combination, a feed dog carrying frame, a rocking arm to which said frame is pivoted at one end, a feed dog carried by the other end of said frame, a link pivoted to said frame between the feed dog and the rocking 125 arm, means for moving said link whereby said feed dog carrying frame is moved back and forth, a second link pivoted to said feed dog carrying frame, between the feed dog and the rocking arm, and means connected 130

to said link for oscillating the frame upon its pivotal connection with the rocking arm.

9. A feeding mechanism including in combination, a feed dog carrying frame, a feed dog mounted thereon, a rocking arm to which one end of the frame is pivoted, a link pivoted to the frame, and lying substantially parallel therewith, a rotating crank pin connected to said link for moving the frame back and forth, a second link pivoted to the frame and lying substantially at right angles thereto, and a rock shaft connected to the lower end of said link for oscillating said frame on its pivotal connection with the rocking arm.

10. In a feeding mechanism, a feed bar and a feed dog, a work support, means to give said feed bar a work-feeding and a vertical movement, said means for giving the work-feeding movement being adjustable, and additional means to position said feed dog horizontally in the work support whereby its feeding position may be varied, said positioning means including an eccentric pin having engagement with said feed bar.

11. In a feeding mechanism, a feed bar

and a feed dog carried thereon, means to give said feed dog a work-feeding movement and a vertical movement, said vertical movement having means of adjustment, said means for moving the feed dog vertically including a rocking shaft, an arm carried thereon, and means carried by said arm to adjust it upon said shaft.

12. In a feeding mechanism, a feed bar and a feed dog carried thereon, means to give said feed dog a work-feeding and a vertical movement, said vertical movement having means of adjustment including a shaft, an arm carried thereon, said arm having set screws located upon opposite sides of a central line passing through said shaft, whereby in the loosening of one screw and the tightening of the other, the arm is moved angularly upon its support.

In testimony whereof I affix my signature in presence of two witnesses.

DUDLEY S. SEYMOUR.
